[57] CLAIM

The ornamental design for a support for a television set, as shown and described.

DESCRIPTION

FIG. 1 is a side elevational view of a support for a television set showing my new design, the opposite side being a mirror image thereof;

FIG. 2 is a top plan view;

FIG. 3 is an end elevational view, the opposite end being a mirror image thereof;

FIG. 4 is a top plan view with the upper portion removed for convenience of illustration;

FIG. 5 is a perspective view; and,

FIG. 6 is a perspective view thereof with the upper portion being rotated to an alternate position.

FIG.1

FIG.2

FIG.3

FIG.4
